CLAIM

The ornamental design for a paper scissors, as shown
and described.

DESCRIPTION

FIG. 1 is a top plan view of a paper scissors embodying
my new design, the other side being substantially a
mirror image thereof;

FIG. 2 is a side elevational view of same from the bot-
tom of FIG. 1, the other side being a substantial mirror
image thereof;

FIG. 3 is an end elevational view of same taken from
the right-hand end of FIG. 2; and

FIG. 4 is an end elevational view of same taken from
the left-hand end of FIG. 2.
